United States Patent Office

Des. 199,095
Patented Sept. 8, 1964

199,095

MACHINE FOR FILLING AND TRANSFERRING CONTAINERS

John B. West, Pikesville, Md., assignor to Maryland Cup
Corporation, Owings Mills, Md., a corporation of
Maryland

Filed Sept. 23, 1963, Ser. No. 76,698

Term of patent 14 years

(Cl. D55—1)

FIG. 1.

FIG. 5.

Des. 199,095

PAGE 2

FIG. 2.

FIG. 6.

FIG. 3.

FIG. 4.

FIG. 1 is a front elevational view of a machine for filling and transferring containers, showing my new design;

FIG. 2 is a rear elevational view thereof;

FIG. 3 is a side elevational view thereof from the left side of FIG. 1;

FIG. 4 is a side elevational view thereof from the right side of FIG. 1;

FIG. 5 is a top plan view thereof; and

FIG. 6 is a bottom plan view thereof.

The dominant features of my design reside in the portions shown in full lines.

I claim:

The ornamental design for a machine for filling and transferring containers, as shown and described.
